(57) **CLAIM**

I claim the ornamental design for a dough shaping tool, as shown and described.

DESCRIPTION

FIG. 1 is a top perspective of a dough shaping tool.
FIG. 2 is a bottom perspective of the dough shaping tool of FIG. 1.

FIG. 3 is a front elevation view of the dough shaping tool of FIG. 1.

FIG. 4 is a rear elevation view of the dough shaping tool of FIG. 1.

FIG. 5 is a right side elevation view of the dough shaping tool of FIG. 1.

FIG. 6 is a left side elevation view of the dough shaping tool of FIG. 1.

FIG. 7 is a top plan view of the dough shaping tool of FIG. 1; and,

FIG. 8 is a bottom plan view of the dough shaping tool of FIG. 1.

The broken lines depict portions of the dough shaping tool that form no part of the claimed design.
